UNITED STATES PATENT OFFICE.

DAVID D. MACCORMACK AND MARY A. MACCORMACK, OF BOSTON, MASSACHUSETTS.

CARRIER FOR LAUNDRY ARTICLES.

1,385,695.

Specification of Letters Patent. Patented July 26, 1921.

Application filed December 28, 1920. Serial No. 433,680.

To all whom it may concern:

Be it known that we, DAVID D. MACCORMACK and MARY A. MACCORMACK, citizens of the United States, residing at Boston, in the county of Suffolk and State of Massachusetts, have invented new and useful Improvements in Carriers for Laundry Articles, of which the following is a specification.

10 The invention relates to a carrier or wrapper in which a bunch or pile of assembled articles, such as fabrics to be sent to, or returned from a laundry, may be confined and transported.

15 The object of the invention is to provide a strong and durable carrier or wrapper, adapted to be quickly and conveniently adjusted and confined around a pile of articles, to securely confine the pile, and also adapted to be quickly and conveniently opened, and to be easily washed and kept in a clean and sanitary condition.

20 The invention is embodied in the improved carrier hereinafter described and claimed.

25 Of the accompanying drawings forming a part of this specification,—

Figure 1 is a plan view of a carrier embodying the invention, spread out in a flat condition.

30 Fig. 2 shows the carrier partly wrapped around a pile of articles.

Fig. 3 shows the carrier completely wrapped around and secured to the pile.

35 Fig. 4 shows the carrier differently wrapped and secured.

The same reference characters indicate the same parts in all of the figures.

In carrying out our invention we fashion 40 a sheet of flexible material, preferably cotton cloth, in such manner that the sheet, when spread on a flat surface, forms a central portion on which articles to be wrapped may be loosely assembled to form a pile 13, indicated by dotted lines in Fig. 1, and a marginal portion surrounding the central portion.

45 Said marginal portion includes two straight-edged longitudinal flaps 14, provided with orifices 16 at their opposite ends, and two peaked transverse flaps 17, the edges of which are reentrantly curved and form obtuse angles by their intersection with the straight edges of the flaps 14, and 55 acute angles or peaks by their intersection with each other.

The longitudinal flaps 14 are adapted to be folded across the top of the pile and overlapped, as shown by Fig. 2, until the orifices 16 in each flap register with those in the other. The form of the peaked flaps 17 and the size of the orifices 16, are such that the outer portion or peak of each flap may be threaded through two coinciding orifices, as shown at the left by Fig. 2. This operation 60 puckers the base portions of the flaps 17 and draws said base portions toward the ends of the pile 13. In case the pile is oblong and is arranged as indicated by Fig. 1, a continued pull on the portions passed 65 through the orifices 16, folds the end portions of the flaps 14, and portions of the flaps 17 inwardly as shown by Fig. 3, so that the base portions of the flaps 17 are drawn closely against the ends of the pile, and all 70 the surfaces of the pile are covered. To the peaks of the flaps 17 are fixed elongated flexible strips 19, which are composed of tape, and are long enough to be wrapped around the carrier and tied, thus confining 75 all the flaps in position to cover and confine the pile 13.

The corners of the flaps 14 are preferably reinforced by fabric corner pieces, in which the orifices 16 are formed, said orifices 80 being reinforced by button-hole stitches. The carrier including the tapes 19, is, therefore, adapted to be easily washed.

Any suitable part of the carrier may be inscribed with a laundry number, identifying 85 the carrier and its contents.

Instead of wrapping the strips 19 around the carrier and its contents, said strips may be tied together above the carrier, so that they will form, with the threaded portions 90 of the flaps 17, a bail by which the carrier may be transported.

The described carrier constitutes a very desirable, economical, and readily identifiable substitute for wrapping paper and 100 string usually employed in wrapping laundry packages.

The carrier is usually secured as shown by Figs. 2 and 3, in wrapping soiled articles to be sent to a laundry, the articles being 105 piled promiscuously and crowded together by the carrier, when the latter is finally adjusted, as shown by Fig. 3, there being no occasion for keeping the articles smoothly folded. When the articles have been washed 110 and ironed, and are ready to be sent home, the carrier is preferably adjusted as shown

by Fig. 4, to confine the articles forming the pile in a smooth, flat condition. In thus adjusting the carrier, the longitudinal flaps 14 are drawn snugly against the pile, one 5 of said flaps overlapping the other to any extent required, no attempt being made to register the orifices 16. The peaked flaps 17 are then drawn snugly against the ends of the pile, and against the outer longitudinal flap 14, and are then crossed and their 10 extremities are extended in opposite directions. The tapes 19 are then wrapped around the carrier and tied together, as indicated at 19^a to bind the carrier upon its contents. 15 The attenuated outer portions of the flaps 17 are adapted to be conveniently grasped and pulled in opposite directions, to locate and cross the flaps as shown, preparatory to the binding operation. Said attenuated 20 portions are also adapted to be compressed and crossed upon each other, as best shown by Fig. 4, and thus form portions of ligatures, other portions of which are formed by the tapes.

25 We claim:

1. A washable carrier of the character stated, comprising a flexible sheet having a central portion on which articles may be assembled in a pile, and a marginal portion 30 surrounding said central portion; said marginal portion including two straight-edged longitudinal flaps, provided with reinforced orifices at their opposite ends, and adapted to be overlapped at the top of the pile, with 35 the orifices in one flap registering with those

in the other flap, and two peaked transverse flaps formed to cover opposite ends of the pile, and having attenuated portions adapted to be threaded through registering orifices in the longitudinal flaps, and thereby 40 draw the base portions of the peaked flaps toward the ends of the pile, and flexible tapes attached to the peaks of the transverse flaps, the outer attenuated portions of 45 the transverse flaps being compressible and adapted to cross each other and form portions of confining ligatures, other portions of which are formed by said tapes.

2. A washable carrier of the character stated, comprising a flexible sheet having a central portion on which articles may be assembled in a pile, and a marginal portion surrounding said central portion, and including two straight-edged longitudinal flaps, adapted to be overlapped at the top 50 of the pile, and two peaked transverse flaps, formed at their outer end portions to be grasped and drawn in opposite directions, toward the ends of the pile; and flexible tapes attached to the peaks of the transverse flaps, the outer attenuated portions 55 of the transverse flaps being compressible and adapted to cross each other and form portions of confining ligatures, other portions of which are formed by said tapes. 60

In testimony whereof we have affixed our signatures.

DAVID D. MACCORMACK.
MARY A. MACCORMACK.
